(57) **CLAIM**

The ornamental design for an accessory riser mount, as shown and described.

DESCRIPTION

FIG. 1 is a perspective view of the accessory riser mount in accordance with the present invention;

FIG. 2 is a top view thereof;

FIG. 3 is a left side view thereof, the right side view being the same;

FIG. 4 is a bottom view thereof; and,

FIG. 5 is a front end view thereof, the rear end view being the same.

The broken lines shown in the drawings represent unclaimed portions of the design and form no part thereof.
